No. 36,375.

Patented June 23, 1903.

UNITED STATES PATENT OFFICE.

WILLIAM H. KOHR, OF SALINA, KANSAS.

DESIGN FOR A WINDOW-SHELF BRACKET.

SPECIFICATION forming part of Design No. 36,375, dated June 23, 1903.

Application filed May 7, 1903. Serial No. 156,211. Term of patent 7 years.

To all whom it may concern:

Be it known that I, WILLIAM H. KOHR, a citizen of the United States, residing at Salina, in the county of Saline and State of Kansas, have invented a new, original, and ornamental Design for a Window-Shelf Bracket, of which the following is a specification, reference being had to the accompanying drawing, forming part thereof.

The drawing illustrates the invention in perspective.

What I claim is—

The ornamental design for a window-shelf bracket, as shown.

In testimony whereof I affix my signature in the presence of two witnesses.

WILLIAM H. KOHR.

In presence of—

W. S. BULKLEY,
B. J. LITOWICH.
